UNITED STATES PATENT OFFICE.

ISAAC N. MEDSKER AND CHARLES W. WINKLE, OF INDIANAPOLIS,
INDIANA.

BAG-HOLDER.

No. 797,303.

Specification of Letters Patent.

Patented Aug. 15, 1905.

Application filed December 12, 1904. Serial No. 236,618.

To all whom it may concern:

Be it known that we, ISAAC N. MEDSKER and CHARLES W. WINKLE, of Indianapolis, county of Marion, and State of Indiana, have invented a certain new and useful Bag-Holder; and we do hereby declare that the following is a full, clear, and exact description thereof, reference being had to the accompanying drawings, in which like figures refer to like parts.

The object of this invention is to provide a new and improved bag-holder that is capable of holding the mouth of the bag wide open for filling purposes and is readily detached from the bag.

The nature of the invention will be understood from the accompanying drawings and the following description and claims.

In the drawings, Figure 1 is a rear elevation of the bag-holder supporting a bag. Fig. 2 is a side elevation thereof supporting the bag. Fig. 3 is the same as Fig. 2 with the bag-holder detached after the bag has been filled. Fig. 4 is a plan view of the device in the condition shown in Fig. 3. Fig. 5 is a plan view of the device while holding a wide bag. Fig. 6 is a plan view of the device while holding a small bag. Fig. 7 is a bottom view of the catch construction, parts being broken away. Fig. 8 is a vertical section of the upper part of the device in the condition shown in Fig. 2 and on the line 8 8 of Fig. 4, a part being broken away.

In detail, 10 represents a platform on which there are two uprights 11 secured to the angle-braces 12. Supports 13 are secured to said uprights, and their upper ends are turned horizontally and parallel with each other. Upon the upper ends of said supports a board 15 is secured by bolts and the nuts 16. Another board 17, of substantially the same dimensions, is secured to the board 15 by the hinges 18. Said hinges are secured to the top side of the board 15 and the bottom side of the board 17 as the latter board lies upon the former, so that the top board can be turned from the position shown in Fig. 2 to that shown in Fig. 3. On the board 17, as seen in Figs. 5 and 6, a pair of bag-holding arms 20 and 21 are secured, the former being rigidly secured in place and the latter adjustably secured by means of a set-screw 22, that operates through the slot 23 of the board 17, whereby the arm 21 may be moved closer to the arm 20, from the position shown in Fig.

5 to the position shown in Fig. 6, to accommodate a smaller bag. These arms 20 and 21 have upwardly-extending prongs 24, upon which a bag 25 is caught at its corners.

When the board 17 is folded back into the position shown in Fig. 2, said arms 20 and 21 extend horizontally and support the bag, as shown in Figs. 1, 2, 5, and 6. The top board 17 is held in said folded position by a latch 27, that is engaged and held by the sliding catch 28, as shown in Figs. 7 and 8. Said sliding catch 28 is mounted in a recess 29 on the under side of the board 15, as shown in Fig. 7, and over a pair of straps 30, and it is actuated positively by either of two levers 31, that are fulcrumed at 33 upon the board 15, as shown in Fig. 4, and the inner ends of these levers are turned downward through an opening 32 in the board 15 and secured to the sliding catch 28. The levers 31 extend laterally beyond either side of the device, whereby it is convenient for the operator to reach the same with his hand or body, and when they are moved in the direction indicated by the arrow in Fig. 4 the catch 28 will be moved inward from the position shown in Figs. 4, 7, and 8 and release the latch 27. Thereupon the spring 36 throws the top board 17 from the folded position shown in Fig. 2 to the position shown in Fig. 3. This movement of said board 17 causes the downward and releasing movement of the bag-holder arms 20 and 21 to the position shown in Fig. 3, said parts being stopped in their movement by the stop 37 on the under side of the board 15. Said catch 28 immediately after operation is returned to its normal position by a spring 39.

The spring 36 is mounted in connection with a hinge 49, secured to the two boards 15 and 17, as shown in Fig. 4; but it may be mounted in any other way desired.

The supports 13 are slidable vertically through holders 40 and are held in position by the lower holder 40 being clamped by the clamp 41 to the upright 11.

What we claim as our invention, and desire to secure by Letters Patent, is—

1. A bag-holder including bag-holding arms pivotally mounted so as to be movable downward from a horizontal position, a spring for bringing about said downward movement of said arms, and releasable means for holding said arms in a horizontal position.

2. A bag-holder including a board pivot-

ally mounted at one edge, bag-supporting arms secured thereon, a spring tending to move said board so as to release said bag-holding arms from the bag, and a latch for holding said board in a bag-holding position.

3. A bag-holder including a board pivotally mounted at one edge, bag-supporting arms secured thereon, one of said arms being secured to said board so as to be adjustable toward or away from the other arm, a spring tending to move said board so as to release said bag-holding arms from the bag, and a latch for holding said board in a bag-holding position.

4. A bag-holder including a stationary board, a movable board thereon, the inner adjacent edges of the boards being pivotally connected, bag-holding arms secured upon the movable board when in a folded position, a spring that tends to move said movable board from the folded position, and a latch for holding said movable board in its folded position.

5. A bag-holder including a board pivotally mounted at one edge, bag-supporting arms secured thereon, a spring tending to move said board so as to release said bag-holding arms from the bag, a latch for holding said board in a bag-holding position, and a movable catch for engaging said latch.

6. A bag-holder including a board pivotally mounted at one edge, bag-supporting arms secured thereon, a spring tending to move said board so as to release said bag-holding arms from the bag, a latch for holding said board in a bag-holding position, a movable catch for engaging said latch, and a lever extending beyond the side of the device for operating said catch.

7. A bag-holder including a board pivotally mounted at one edge, bag-supporting arms secured thereon, a spring tending to move said board so as to release said bag-holding arms from the bag, a latch for holding said board in a bag-holding position, a movable catch for

engaging said latch, a lever extending beyond the side of the device for operating said latch, and a spring for returning said catch to its normal position.

8. A bag-holder consisting of a support, a board secured to said support stationary, a movable board lying upon said stationary board, means for pivotally connecting said boards at their inner adjacent edges, bag-holding arms secured to said movable board when in a folded position, a latch secured to said movable board for holding it in a folded position, a slid able catch mounted in connection with said stationary board for engaging the latch and holding it, a lever extending beyond the side of the device for actuating said catch to release the latch, and a spring tending to move said movable board from the folded position.

9. A bag-holder consisting of a support, a board secured to said support stationary, a movable board lying upon said stationary board, means for pivotally connecting said boards at their inner adjacent edges, bag-holding arms secured to said movable board when in a folded position, a latch secured to said movable board for holding it in a folded position, a slid able catch mounted in connection with said stationary board for engaging the latch and holding it, a lever extending beyond the side of the device for actuating said catch to release the latch, a spring tending to move said movable board from the folded position, and a stop to limit the releasing movement of said arms and movable board.

In witness whereof we have hereunto affixed our signatures in the presence of the witnesses herein named.

ISAAC N. MEDSKER.
CHARLES W. WINKLE.
